UNITED STATES PATENT OFFICE.

WILLIAM M. SCHOLL, OF CHICAGO, ILLINOIS.

TOE-SPREADER.

1,080,304.

Specification of Letters Patent.

Patented Dec. 2, 1913.

Application filed January 22, 1912. Serial No. 672,598.

To all whom it may concern:

Be it known that I, WILLIAM M. SCHOLL, a citizen of the United States, residing at Chicago, in the county of Cook and State 5 of Illinois, have invented certain new and useful Improvements in Toe-Spreaders, of which the following is a specification.

My invention relates to improvements in toe-spreaders, and has for its general object to provide a simple and efficient structure which may be applied to the human foot with comfort and ease for the wearer, to spread apart the toes, thereby to aid in the correction of bunions, soft corns and 15 other troubles arising from the displacement of the toe phalanges, crowding of the toes and dislocation of the joints.

In the drawings, wherein I have shown an embodiment of my invention; Figure 1 is a plan view showing the application of the device to the human foot; Fig. 2 is a plan view with the post in section; Fig. 3 is a longitudinal section taken on line 3—3 of Fig. 2; Fig. 4 is a transverse section on line 4—4 of Fig. 2; Figs. 5 and 6 are details of supplemental reinforcing pillars.

In the treatment of many foot ailments, and particularly in the treatment of bunions, it is desirable to interpose a spreader 30 between the great toe and the second toe, thereby to force the phalanges of the great toe back toward normal position. In the provision of such toe spreaders it is important and desirable that the spreader be of a 35 character which may comfortably be worn during the day-time; that it may be susceptible of adjustment as to its spreading effect, not to impose too severe or painful a straightening pressure upon the distorted 40 great toe; that it be capable of ready application and shall not constrict any toe to impede circulation; that it shall remain in adjusted position; and, in many instances, that a spreading agent be interposed between the 45 second toe and the middle toe, as the second toe is apt to be more or less distorted by the lateral pressure of the great toe.

For the attainment of these and other desiderata my invention contemplates the provision of a spreader structure, one specific embodiment of which is shown in the drawing, and which embodiment I will now specifically describe.

10 and 11 indicate respectively base and 55 top members, preferably of similar oval form, connected by a continuous wall 12

forming an oval preferably tapering toward its rear end; said wall, base and top members being preferably made integrally of a suitably molded piece of rubber to constitute jointly an ovate, open-centered spreader-member with top and bottom flanges extending therefrom in parallel planes to underlie and overlie, respectively, the adjacent toes.

Near its front end the ovate wall 12 is 60 preferably thickened on its inner side surfaces to form vertical stiffening ribs 13, to resist deflection at that point to a greater extent than do the thinner walls in rear of the ribs. Said ribs 13 are preferably dished on 65 their inner surfaces as at 14, to form in each separate side wall a retaining seat portion in which a plug or post may be fitted to be retained against displacement longitudinally of the spreader. For insertion in such seat 70 75 a cylindrical, resilient plug 16 may be employed, two forms of plugs being shown respectively in Figs. 5 and 6, the plug 16^a of Fig. 5 consisting of a section of rubber tubing having walls of suitable thickness for 80 the intended increase in resistance to deflection, and the other plug 16^b shown in Fig. 6 consisting of a closed air-containing cylinder of rubber or other flexible material which may be employed as a pneumatic 85 cushion, and having a resistance to compression depending upon the inflation of the cushion. By the insertion of plugs of different degrees of resistance or compression the spreading effect of the reinforced front 90 end of the device may be varied, the maximum resistance being localized in any event to the front end of the spreader.

This arrangement presents advantages, as 95 the maximum spreading effect takes place near the end of the toe, where the greatest leverage is available, while the rear end of the structure is more readily conformable to the shape of the toes for greatest comfort. As indicated in Fig. 1 the reinforcing plug 100 may spread longitudinally under pressure, but is definitely retained in desired position. For additional advantage I prefer that the base member 10 have a lateral extension 20 of suitable extent to project under the second toe, and having a thickened portion 21 formed to extend up along side of the second toe to insure retention of the device in desired position. The interposition of the spreading portion 21 between the second and 105 middle toes has the effect of crowding the second toe toward the great toe and to an-

chor the structure the more securely against unintentional displacement.

While I have herein described in some detail a particular embodiment of my invention it will be seen that changes in details thereof might be made without departure from the spirit of my invention and within the scope of the appended claims.

What I claim is:

- 10 1. A toe-spreading appliance formed of a material having the essential qualities of rubber and comprising in a unitary structure a base, and a single hollow post, relatively long and narrow, rising above said base, said post being formed with a single uninterrupted ovate wall, thin and flexible throughout its rear portion and interiorly thickened for greater stiffness near the forward portion thereof.
- 15 2. A toe-spreader comprising a spreading post having transversely extending top and bottom flanges, and a toe-spreading appliance comprising a continuing ovate wall having thickened portions near its front end shaped to provide opposing seats, and a plug arranged for insertion into and retention by said seats.
- 20 3. A toe-spreader comprising a spreading post having transversely extending top and bottom flanges, and a toe-spreading appliance comprising a continuing ovate wall having thickened portions near its front end shaped to provide dished opposing seats, and a hollow plug arranged for insertion into and retention by said seats.
- 25 4. A toe-spreader comprising a spreading post having transversely extending top and bottom flanges, and a toe-spreading portion comprising a continuing ovate wall having

thickened portions near its front end shaped 40 to provide a plug retaining seat, and a pneumatic plug.

5. The combination with a toe-spreader having resilient walls surrounding an opening, and a removable sealed air containing 45 filler for said opening.

6. A bunion correcting appliance comprising, in combination, a toe-spreader post adapted to fit between the affected great toe and the second toe, to force the great toe toward natural position, and a spreader extension, not so thick as said post, shaped to extend from the base of the post around the second toe, toward the upper edge of the spreader post, to exert its spreading action 55 between the second and third toe, and transmit an increased proportion of the corrective pressure of the device to the third and smaller toes for the purposes described.

7. The combination of a toe-spreader post 60 adapted to fit between the great toe and the second toe, a base flange extending horizontally therefrom to underlie said toes, and a spreader extension, narrower than the length 65 of the base flange, projecting from its lateral edge, shaped to extend around the second toe between it and the third toe, toward, but spaced apart from, the upper edge of said spreader post, said extension being 70 thicker than the base, and all made integrally of rubber.

In testimony whereof I hereunto set my hand in the presence of two witnesses:

WILLIAM M. SCHOLL.

In the presence of—

W. LINN ALLEN,
MARY F. ALLEN.
